CLAIM

The ornamental design for a galley with curved stair and built-ins, as shown and described.

DESCRIPTION

FIG. 1 is a perspective view of a galley with curved stair and built-ins;

FIG. 2 is a side view of the galley with curved stair and built-ins of FIG. 1;

FIG. 3 is a side view of the galley with curved stair and built-ins of FIG. 1 opposite the view of FIG. 2;

FIG. 4 is an end view of the galley with curved stair and built-ins of FIG. 1;

FIG. 5 is an end view of the galley with curved stair and built-ins of FIG. 1 opposite the view of FIG. 4;

FIG. 6 is a top view of the galley with curved stair and built-ins of FIG. 1; and,

FIG. 7 is a bottom view of the galley with curved stair and built-ins of FIG. 1.

The broken lines shown are included for the purpose of illustrating the unclaimed portions of the article and forms no part of the claimed design.
